UNITED STATES PATENT OFFICE.

MOSES AARON, OF CINCINNATI, OHIO.

DESIGN FOR A TIRE.

Application filed October 10, 1919. Serial No. 329,883. Term of patent 3½ years.

To all whom it may concern:

Be it known that I, MOSES AARON, a citizen of the United States, residing at Cincinnati, in the county of Hamilton and State of Ohio, have invented a new, original, and ornamental Design for Tires, of which the following is a specification, reference being had to the accompanying drawing, forming part thereof.

Fig. 1 is a perspective view of a portion of a tire illustrating the design; and

Fig. 2 is a plan view representing a portion of said design.

I claim:

The ornamental design for a tire, substantially as shown.

MOSES AARON.
